INVENTOR
EDWIN T. BLAKE

BY
Victor J. Evans
ATTORNEY

UNITED STATES PATENT OFFICE.

EDWIN T. BLAKE, OF BERKELEY, CALIFORNIA.

MEANS FOR REINFORCING EXCAVATOR-BUCKET TEETH.

Application filed March 14, 1923. Serial No. 625,083.

To all whom it may concern:

Be it known that I, EDWIN T. BLAKE, a citizen of the United States, residing at Berkeley, in the county of Alameda and 55
5 State of California, have invented new and useful Improvements in Means for Reinforcing Excavator-Bucket Teeth, of which the following is a specification.

This invention relates to means for reenforcing 60
10 excavator bucket teeth and has for its primary object the provision of manganese steel webs which are disposed on the teeth adjacent the cutting points thereof.

A further object is to provide reenforcing means which will prevent a wearing of 65
15 the tooth per se and the edge of the bucket and at the same time prevent distorting of the point.

A still further object is to provide means 70
20 whereby the wedging of stones between the teeth will be prevented.

Other objects and advantages will be apparent during the course of the following description.

25 In the accompanying drawings forming a part of this specification, and in which like numerals are employed to designate like parts throughout the same,

Figure 1, is a perspective view of a tooth 75
30 constructed in accordance with my invention and showing a removable point in dotted lines,

Figure 2 is a fragmentary top plan view 80
35 of a bucket showing two teeth secured thereto.

Applicant is aware of the fact that wearing points have been provided for bucket teeth. These wearing points, however, merely protected the tooth itself and often 85
40 caused stones to become jammed between the teeth, which stones are hard to remove.

Applicant has overcome these objections by applying his novel means for reenforcing the teeth and disposing means upon each 90
45 side of the tooth, which extend forwardly therefrom and contact the sides of the ordinary removable point, the adjacent flanges or flared portions of the two teeth lying relatively close together thereby preventing the 95
50 wedging of stones between the teeth and at the same time protecting the digging edge of the bucket against undue wear.

In the accompanying drawings wherein 100
for the purpose of illustration is shown a

preferred embodiment of my invention, the numeral 5 designates a portion of the bottom of a bucket having teeth designated as a whole by the numerals 6 and 7 secured thereto. By referring to Figure 1, it will be noted that this tooth is provided with an elongated portion 8 which overlies the bottom of the bucket, while a portion 9 underlies the bottom of the bucket, or vice versa. 105

These portions 8 and 9 are spaced from each other to accommodate the thickness of 110
the bucket bottom and are joined together by a pointed tip portion 11.

A longitudinal channel 12 extends the length of the tooth and also divides the point of the tooth. 115

At 13 I have shown a point preferably formed of a wear resisting material, such as manganese steel which point is adapted to be bolted or riveted to one of the teeth as for instance the tooth 7. This point is provided with a rearwardly extending lug 14 adapted to receive a bolt or rivet 16 which passes through a suitable opening in the tooth 7. 120

A similar rivet or bolt as shown in dotted lines at 17 passes between the tip 11 and serves to prevent side motion of the point. 125

At 18 and 19 I have shown flared portions formed integral with the tips 11 and extending forwardly to a point adjacent the centers of the tip. 130

By viewing Figure 1, it will be noted that these flared portions about the side of the point 13 which also assist in preventing movement of the point with respect to the tooth. 135

These flared portions of each respective tooth is adapted to lie in close proximity to each other as best shown in Figure 2. This serves to prevent stones of any size wedging themselves between the teeth and at the same time prevents the digging edge 19 of the bucket 5 from coming into direct digging contact with the earth thereby saving considerable in the wear of the bucket. 140

It will thus be seen that I have provided reenforcing means for a bucket tooth which will accomplish the objects set forth. 145

It is to be understood that the form of my invention herewith shown and described is to be taken as a preferred example of the same, and that various changes in the shape, size and arrangement of parts may be resort- 150

ed to without departing from the spirit of the invention or the scope of the subjoined claim.

Having thus described my invention, I

5 claim:—

In a device of the character described the combination of a bucket tooth having a removable point adapted to be attached to said tooth, flared portions formed integral with

said point and on a plane parallel to the 10 length of the tooth, said flared portions being curved from the front toward the rear, and adapted to contact the sides of said point, substantially as and for the purpose specified.

In testimony whereof I affix my signature.

EDWIN T. BLAKE.
